METHOD AND MEANS FOR LOADING AND TRANSPORTING MERCHANDISE

Robert V. Sanford, Hartford, Conn., assignor to
The Stanley Works, New Britain, Conn., a cor-
poration of Connecticut

Application June 12, 1936, Serial No. 84,781

6 Claims. (Cl. 105—369)

This invention relates to a method and means for loading and transporting merchandise.

Heretofore there have been two common methods for supporting merchandise on railway cars and other carriers, and they are usually referred to as the fixed-load method and the floating-load method.

In the fixed-load method, the merchandise is rigidly secured to the floor and sides of a vehicle by means of cleats, braces, and tie members, thus subjecting the merchandise to sudden shocks, bumps, and jars during transportation which tend to injure it, frequently resulting in its breaking loose from its bracing. This rigid bracing not only proves expensive, but is usually injurious to the floor and walls of the transporting vehicle since the braces must be nailed or bolted thereto. Furthermore, there is considerable loss of time during loading and unloading of the merchandise and rigidly securing it in position.

In the floating-load method, the merchandise is bound into a unit load of such mass or weight that its inertia tends to resist shifting movement, and instead of rigidly securing it in position to the floor of the transporting vehicle, the unit load is allowed to move somewhat under excessive jars and shocks. In this method, the combined inertia and friction between the load and the vehicle floor is intended to absorb shocks and jars and prevent undue and excessive movement of the merchandise during shipment. However, it has been found, particularly in rail shipment, that the transportation of merchandise by this floating-load method is not entirely satisfactory due to excessive shifting movement of the merchandise. In most cases severe shocks occur in transit, which may cause an accumulated shift or movement of the units from their original position in the car great enough to block the doorways and thereby making it almost impossible to remove the skids from the car without difficulty and extra expense and also causing a very disagreeable situation at the receivers' end. The accumulated movement of the units may also be toward the ends of the car, causing damage to both the merchandise and the car.

It is an aim of my invention to provide a convenient method and means for mounting merchandise in grouped unit loads on a vehicle in such manner that the merchandise may be quickly and easily loaded and unloaded and whereby the shifting of a load of merchandise, such as skids of paper, may be controlled and retarded, but yet permitting adequate movement to absorb the severe shocks occurring in transit to such an

extent as to relieve the units from undue strains and stresses, thereby preventing excessive shifting.

With these and other objects in view, my invention resides in the novel combination and construction of parts hereafter described, illustrated in the accompanying drawing, and referred to in the appended claims; it being understood, of course, that the disclosure shown in the drawing is simply by way of illustration, and various minor details of constructional changes lying within the scope of the claims may be resorted to without deviating from the spirit of the invention or sacrificing any of its advantages.

Referring to the drawing wherein like parts are indicated by like numerals:

Figure 1 is a perspective view showing my invention associated with a plurality of elements grouped into a unit ready for shipment; and

Fig. 2 is a fragmentary view of one of the skids arranged to support a load element and having an abrasive coated portion adapted to frictionally engage the vehicle floor and restrain movement of the load during shipment.

Referring to the drawing in detail, I have provided a portable shipping platform 10 having a pair of spaced skids 11 rigidly secured to its under side and arranged to engage a vehicle floor and support the platform in spaced relation thereto for convenient movement. A load element 12, illustrated in the present instance as a rectangular pile of sheet material such as paper but which may comprise any suitable merchandise, is rigidly secured on the platform 10 by means of a series of transversely and longitudinally extending binding straps 14 passing around the load and platform to rigidly secure the load and platform together. Each of the straps 14 may be suitably secured in tensioned relation and fastened together by a sealing member 15 of any suitable type and preferably a sealing member of the type disclosed in the United States patent to Prindle No. 1,981,371 issued on November 20, 1934. The skids 11 may be provided with spaced cut-away portions 16 adjacent to the under side of member 10 whereby the transverse binding straps 14 may be passed between members 10 and 11. Longitudinal straps 14 are secured in spaced relation and preferably pass along the under side of member 10 adjacent to the respective skid members 11. As shown in Fig. 1, a plurality of load elements 12 may be grouped together into a unit load and firmly banded in abutting relationship by binding straps 18 passing around the entire load and secured together by seals 19.

These straps and seals may be of the same type as straps 14 and seals 15.

In accordance with the present invention, and in order that the shifting of the load of merchandise may be controlled and restrained, I provide abrasive coated portions 20 on the floor contacting surfaces 21 of skids 11. These coatings are preferably composed of a suitable retarding medium such, for example, as a bonded abrasive material composed of abrasive grains of alumina or silicon carbide, commonly referred to by the trade names "alundum", "carborundum", "cristolon", etc. This invention also contemplates the use of other suitable sharp granular materials such as metal chips, sand, garnets, etc.

My preferred method of preparing the bottom faces 21 of skids 11 to form the coatings 20 is to first coat spaced portions on said faces with a liquid adhesive bond such as glue, latex cements, 20 paints, resinous cements, lacquers, or other suitable adhesives adapted to quickly dry and harden and provide suitable bonding agents within the range of normal atmospheric temperatures. After the spaced portions on surfaces 21 have 25 been coated with bond, and while it is still wet, abrasive grains of desired size and composition are sprinkled into the bond, thereby providing a multiplicity of closely spaced sharp projecting teeth which become rigidly bonded to the skid 30 and provide frictional portions thereon. These minute teeth project downwardly from the skids and cooperatively engage the vehicle floor, thereby providing a high frictional resistance against movement for the merchandise without preventing movement of the load in the event that it is 35 subjected to excessive impact. It will be appreciated that the extent of movement of the load may be accurately controlled during shipment so that the loads may be free to move sufficiently 40 to absorb shocks and jars, and yet will not move to inaccessible positions.

After the skids have been prepared, the merchandise, such as stacked paper 12, may be located upon the platform 10 and secured in place 45 thereon by the straps 14. Then the load may be individually transferred into the transporting vehicle by means of a truck or the lift platform type. The placing of the loads in the car may be easily carried out, there being no necessity of 50 accurately locating on the floor and beneath the skids separate movement restraining elements. All that is necessary is to wheel the load into position, lower the truck, and then pull the truck out from between the skids. After the elements are 55 positioned within the vehicle, they may be bound into a load unit by the straps or bands 18.

In view of the fact that the abrasive coatings are each composed of a multiplicity of minute sharp projecting teeth, it will be appreciated that 60 no damage will be done to the vehicle floor during shipment, but sufficient friction will be provided to regulate the movement of the unit load. It will be evident that the extent, type, distribution, and size of abrasive grains forming coating 65 20, as well as the bond employed may be easily regulated to meet the demands of any size and type of load which it supports, and, in consequence, any predetermined degree of friction may be easily obtained so that the extent of load 70 movement is properly restrained and controlled.

It is further to be understood that the bonded abrasive coating on the bottom of the skids is substantially rigid and fixedly secured thereto so that there is no tendency of the bond or coating 75 to distort or deform under impacts during

shipment. This abrasive coating will not adhere to the floor since the bond of itself hardens to a rigid body which is not tenacious or gummy, and the abrasive coating produces its frictional characteristics entirely by the cooperative gripping action of a multiplicity of minute sharp projecting abrasive teeth, wherein each of the grains protrudes from the bond and engages a small portion of the vehicle floor without imparting damage thereto.

It is not desired that the present invention be limited to the herein noted abrasive materials and bonds since it is evident that any type of abrasive material can easily be secured to the bottom of a skid to accomplish the same purpose. It is also intended that the scope of the present invention cover an abrasive coated paper or fabric commonly referred to as abrasive paper or cloth and which may be suitably secured to the bottom faces of the skids by nails, cement or other suitable means.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A shipping unit comprising a load of merchandise, a skid supporting said load and having a bottom face engaging a vehicle floor during transportation, and an extremely thin layer of bonding material having a granular abrasive surface between said bottom face and the vehicle floor arranged to frictionally retard the movements of said load relative to the vehicle floor.

2. A shipping unit comprising a load of merchandise, a plurality of skids rigidly secured to and supporting said load, each skid being provided with a bottom face engageable with a vehicle floor during shipment, a layer of bonding material having a granular abrasive surface secured to a portion of the bottom face of each skid and arranged to frictionally engage the vehicle floor whereby movement of the load occasioned by impact will be retarded.

3. A shipping unit comprising a group of articles secured together into a load, a portable platform fastened beneath said load, a plurality of supporting skids rigidly fastened to and supporting the platform, each of said skids having a bottom face slidably engageable with a vehicle floor, and a coating of bonded abrasive material rigidly bonded to the bottom of each skid and having a plurality of sharp abrasive teeth projecting therefrom, said teeth cooperatively engaging the vehicle floor and tending to retard sliding movement of the load under impact.

4. A shipping unit composed of a plurality of load elements, each element including a platform having a plurality of supporting skids rigidly fastened to the under side thereof, each skid having a bottom face slidably engageable with the vehicle floor, a coating of bond adhering to the under side of each skid, and a layer of abrasive grains secured in position by said bond and projecting therefrom and providing outwardly pro-

- jecting teeth, said teeth cooperatively engaging the vehicle floor to frictionally resist a sliding movement of the load during shipment; and means binding said elements into a unit load.
- 5 5. A load supporting skid having a top face adapted to support a load and a bottom face adapted to engage a car floor, said bottom face having alternate gripping and non-gripping surface areas, said gripping surface comprising a 10 layer of bonding material secured to said skid and a layer of sharp-edged minute particles partially embedded in the surface of said bonding material.
6. A shipping unit comprising a supporting platform, a plurality of supporting skids fastened to the under face thereof, the lower face of said skids comprising alternate gripping and non-gripping surfaces, said non-gripping surface having a greater face area than said gripping surface, said gripping surface comprising a layer of bonding material secured to said skid face and having minute sharp-edged particles partially embedded in the surface thereof and projecting therefrom to frictionally engage the supporting 10 surface.

ROBERT V. SANFORD.
